UNITED STATES PATENT OFFICE

JOHN G. HOMAN, OF STEUBENVILLE, OHIO

THERAPEUTIC LAMP

Application filed April 28, 1928. Serial No. 273,558.

This invention relates to therapeutic devices, and more especially to devices in which a lamp or other source of therapeutic rays is employed.

Physical and medical authorities recognize that light has a beneficial effect upon human tissues, especially the blood. Exercise of the body tissue in the presence of a source of light is recognized as being highly beneficial. The exercise stimulates the flow of blood to or near the surface of the body where it is more effectively acted upon by the light rays.

It is of course desirable that the intensity of the light be such as to give the most beneficial results. The intensity of a light varies inversely as the square of the distance from the source. According to the present invention, there is provided a device with which the source of therapeutic rays may be held in fixed relation to the body in close proximity thereto, whereby a lamp of low candle power may function just as effectively as a lamp of much higher candle power located considerably further away from the body.

The invention further contemplates the provision of a therapeutic device so constructed that it will be self-sustaining and can be applied to the body and retained on the body without discomfort.

The invention further contemplates the provision of a therapeutic device as described which can be readily adapted to massage purposes where it is desired to secure a mechanical stimulation of body tissues in conjunction with the treatment thereof by means of light rays.

The invention may be readily understood by reference to the accompanying drawings which illustrate a preferred embodiment of my invention, and in which,

Figure 1 is a view, partly in side elevation and partly in section, showing a device embodying my invention, and

Figure 2 is a view similar to Figure 1, showing the skirt of the vacuum cup turned down to present a massaging surface.

In the drawings 2 designates a base or handle portion of a vacuum cup having sides 3 and a skirt 4. The entire cup is preferably made of soft rubber and is made relatively

light so that it can be self-sustaining on the surface to which it is applied. Mounted in the base 2 is a socket 5 in which is a suitable generator of the desired therapeutic rays, either ultra-violet or infra-red. This generator of therapeutic rays is preferably an incandescent bulb 6 of any known or preferred construction.

Inside of the cup and spaced inwardly from the edge of the skirt 4 is an annular series 60 of rubber fingers or teats 7. The structure as shown in Figure 1 may be pressed against the body of a patient. By reason of its soft rubber construction, it may be temporarily deformed to expel some of the air therefrom.

When it, due to its resiliency, returns to its normal shape, a reduced pressure will exist that serves to hold the appliance on the body in the manner of any ordinary vacuum cup arrangement. Being of comparatively light 70 construction, it can be entirely self-sustaining. Due to the reduced pressure on the interior thereof, blood circulation in the body of the patient will be stimulated and the blood brought close to the surface of the skin. Under these conditions the effect of the light 75 6 is most beneficial.

When it is desired to use the device for massage treatment, the skirt 4 can be turned outwardly to the position shown in Figure 80 2, whereupon the rubber fingers or teats 7 are presented in an operative position for massage purposes. The arrangement then can be used the same as any massage device, and at the same time the massage is being effected, 85 the body is being subjected to the beneficial action of the therapeutic rays.

The surface of the cup is preferably provided with irregularities and ridges such as 8 and 9, by reason of which it can be conveniently handled and held in the hand.

While I have illustrated a specific embodiment of my invention, it will be understood that the invention is not confined to the particular construction shown, but may be otherwise embodied within the scope of the following claims.

I claim:

1. A therapeutic device of the class described comprising a vacuum cup having a 100

skirt portion which can be turned outwardly back over the cup, and a plurality of massaging surfaces on the inside of the cup adapted to project beyond the end of the cup when the skirt is turned backwardly, and a therapeutic lamp mounted inside the cup.

2. A therapeutic appliance of the class described comprising a vacuum cup formed of rubber and having a base portion, a cup portion and a skirt portion, said skirt portion being adapted to be turned backwardly over the cup portion, a plurality of massage fingers on the cup portion and adapted to be exposed when the skirt is turned backwardly, and a therapeutic lamp mounted in the base portion.

3. A therapeutic appliance of the class described comprising a one piece cup formed of rubber and having a base portion, a cup portion, and a skirt portion, said skirt portion being adapted to be turned backwardly over the cup portion, a plurality of massage fingers on the cup portion and adapted to be exposed when the skirt is turned backwardly, and a therapeutic lamp mounted in the base portion, the said cup having ridges on the outside thereof whereby it may be conveniently handled.

In testimony whereof I have hereunto set
30 my hand.

JOHN G. HOMAN.
